UNITED STATES PATENT OFFICE

92,140

DESIGN FOR AN ELECTRICAL CONNECTION PLUG

Joseph Worth, Newark, N. J.

Application March 24, 1934, Serial No. 51,167

Term of patent 7 years

To all whom it may concern:

Be it known that I, JOSEPH WORTH, a citizen of the United States, residing at Newark, in the county of Essex, State of New Jersey, have invented a new, original, and ornamental Design for an Electrical Connection Plug, of which the following is a description, reference being had to the accompanying drawing, forming a part thereof.

In the drawing, the figure is an elevational view of the plug, the view being about twice the size of the actual plug.

I claim:

The ornamental design for an electrical connection plug as shown.

JOSEPH WORTH.
